UNITED STATES PATENT OFFICE.

KARL WIESER, OF BREDENEY, GERMANY, ASSIGNOR TO FRIED. KRUPP AKTIEN-GESELLSCHAFT, OF ESSEN-ON-THE-RUHR, GERMANY.

PROJECTILE-TRACER.

1,108,820.

Specification of Letters Patent. Patented Aug. 25, 1914.

Application filed March 7, 1913. Serial No. 752,671.

To all whom it may concern:

Be it known that I, KARL WIESER, residing at Bredeney, Germany, a subject of the Emperor of Germany, have invented a certain new and useful Improvement in Projectile-Tracers, of which the following is a specification.

The subject matter of the present invention is a projectile tracer, that is a cartridge filled with an illuminating composition and attachable to the shot for the purpose of making the trajectory of the shell visible.

In the drawing is illustrated one embodiment of the present invention and Figure 1 shows a longitudinal section of the projectile tracer with a portion of a shell and cartridge case; and Fig. 2 a section on line 2—2 of Fig. 1 seen from above.

20 The illuminating composition B is enclosed in a casing A of the cartridge, which casing is screwed into the base of the shell C and reaches back into the propelling charge D. To the rear of the illuminating composition B is to be found a retarding composition E and behind the latter a comparatively large chamber F. This chamber is formed by the hollow part of a thimble G which at the same time contains the retarding composition E and is inserted into the casing A in such a manner that it will be driven out from the casing A on the ignition of the illuminating composition. In the bottom of the thimble G are provided 35 small holes g^1 .

On firing the projectile the propelling gases from the charge D penetrate through the fine holes g^1 into the chamber F. As the gases now become considerably throttled, on account of the fine holes, only a small portion of greatly expanded propelling gas enters the chamber F while the projectile still remains in the bore of the gun, and this gas portion ignites the retarding composition E after having expanded in this chamber, which retarding composition subsequently transfers the flame to the illuminating composition B. The thimble G will then first be retained by means of the propelling gases, in the position wherein it keeps the casing A closed but will be ejected from the casing A by the gases generated from the ignition of the illuminating composition B after the shell has left the gun.

55 The flame from the illuminating compo-

sition B will then reach out through the rear of the casing A producing a streak of light which will make the trajectory of the shell visible.

As the ignition of the contents of the described projectile tracer is produced by the propelling gases while expanded or under low pressure and as a consequence no violent excitation of the retarding composition is produced, security of the explosion of the retarding composition (and consequently of the illuminating composition) is assured, and rather a slow burning will take place. For the same reason an illuminating composition may be used which is only slightly compressed and which as a consequence will burn clearly and strongly. This described projectile tracer has moreover the advantage of the greatest possible safety as compared with known projectile tracers which are provided with a fuse for the illuminating composition, which fuse is composed of several parts movable relative to each other; as such a fuse during transport might become active and thereby cause the explosion of the propelling charge of a shot having the arrangement of the projectile tracer as illustrated in the drawing, unless the fuse has been provided with a complicated safety device.

I claim:

1. A projectile tracer comprising a casing secured in the projectile, an illuminating composition in said casing, a thimble closing the rear end of said casing, a chamber between said illuminating composition and said thimble, the rear wall of said thimble having fine holes communicating between said chamber and the space containing the propelling charge for the projectile; whereby only a small portion of considerably reduced tension of the propelling gases is admitted through said holes into said chamber and after further expanding therein ignites said illuminating composition.

2: A projectile tracer comprising a casing secured in the projectile, an illuminating composition in said casing, a thimble closing the rear end of said casing, said thimble being provided with a chamber and a retarding charge interposed between said chamber and said illuminating composition, the rear wall of said thimble having fine holes communicating between said chamber and the space containing the propelling charge for the projectile; whereby only a

small portion of considerably reduced tension of the propelling gases is admitted through said holes into said chamber and after further expanding therein ignites the retarding charge which subsequently ignites the illuminating composition.

The foregoing specification signed at Bar-

men, Germany, this 14th day of February, 1913.

KARL WIESER. [L.S.]

In presence of—

HELEN NUFER,

ALBERT F. NUFER.
